[57] CLAIM

The ornamental design for a collector box for lawnmowers, lawnrakers, or the like, as shown and described.

DESCRIPTION

FIG. 1 is a top and right side perspective view of a collector box for lawnmowers, lawnrakers or the like showing our new design;

FIG. 2 is an enlarged side elevational view taken from the left of FIG. 1;

FIG. 3 is an enlarged front elevational view thereof;

FIG. 4 is an enlarged rear elevational view thereof;

FIG. 5 is an enlarged top plan view seen in the direction of the arrow 5 in FIG. 2;

FIG. 6 is an enlarged bottom plan view thereof; and

FIG. 7 is a reduced rear and left side perspective view thereof.

FIG. 1.

FIG. 2.

FIG.3.
